UNITED STATES PATENT OFFICE.

WILLIAM C. HUSS, OF CINCINNATI, OHIO.

DESIGN FOR A WALL-FIXTURE FOR COUNTERS.

SPECIFICATION forming part of Design No. 23,455, dated July 10, 1894.

Application filed June 2, 1894. Serial No. 513,335. Term of patent 3½ years.

To all whom it may concern:

Be it known that I, WILLIAM C. HUSS, a citizen of the United States, and a resident of Cincinnati, in the county of Hamilton and State of Ohio, have invented a certain new and useful Design for Wall-Fixtures for Counters, of which the following is a specification.

My invention is a new and original design for a wall fixture for counters.

- 10 The leading features of this design are the entablature supported by pilaster columns at the rear, which columns rest upon the sideboard portion at each end; columns resting upon the floor at each end of the sideboard portion and supporting the front corners of the entablature; the cornice, apparently supported at each corner by columns resting upon the architrave above the end supporting columns, and intermediate brackets, the lower 15 ends of which rest upon the rear of the architrave and arch forward under abaci which extend upwardly and break the molding of the cornice; and the arched recesses in the frieze between said brackets, as shown in the accompanying drawings and hereinafter described.

In the drawings, Figure 1 is a front elevation of one-half of a wall fixture embodying my invention. Fig. 2 is a vertical transverse sectional view of the same, taken through line 20 $\alpha\alpha$ of Fig. 1.

The sideboard or closet portion, A, may be of ordinary construction, with the exception of the metal molding finishing strip, a, which covers the top support of sideboard underneath the polished marble top, the said finishing strip, a, terminating at each end in a branched foliated ornament, a', which extends beyond the sideboard end and rests upon the shafts of the columns, B, which support the ends of the entablature, C. The architrave, c, of the entablature, is apparently supported at its rear end by the pilasters, D, which are substantially rectangular in cross section, the lower portions being plain for about one-third of their length, and from that point fluted to the pilaster cap. The flutes upon each side are overlapped by carved foliage which appears to branch from the wall of the side volutes in each column to near the vertical center. Above the capitals of the pilaster columns, and extending across from column to column, is a plain, flat strip,

c', corbelled by an ornamental molding underneath, which rests upon the capitals of the columns. The space between the pilasters, 55 the rear end of the architrave and the top of the sideboard portion is a plain frame fitted with a beveled edge reflecting surface or mirror, E.

The upper fascia of the architrave is a molding, c², which apparently curves around the architrave, above the abacus, b, of the column, B, thence extends across the fixture, but curves outwardly in front of each of the brackets, F, which support the cornice. The outwardly curved portions of the molding, c², 65 have brackets springing from a rounded molding, c³. The lower ends of the brackets and molding upon each side of them have carved ornaments, from which the lower ends of the 70 brackets appear to spring.

The rounded part, b', above the abacus, b, and below the molding, c², of the upper fascia, is plain and is returned back to meet the back wall of the fixture.

The cornice, G, is apparently supported at each end by a plain rectangular support, g, and cluster columns, g', which apparently form the return of the supports supporting the end pieces, g, which extend from the front to the rear of the fixture at each end. The rectangular pieces, g, and columns, g', rest upon the molding, c², and extend up to the lower rounded molding, g², of the cornice, the cluster columns, g', being surmounted by ornamental capitals. 85 The part, b', is enriched by a festoon of foliage, b', which drops from the outer corners and apparently passes through the molding, c², and continues up on the inner edges of the plain portion, g.

The end columns, B, are round and rest upon pedestals, b³, the pedestals having plain base and molded top to match the base of the sideboard, and surbase having enriched molding below it. The neck of the column 95 is enriched with a chevron band, b⁴, of material of a different color or shade from the column, preferably of polished bronze or metal, to make a strong contrast between the column and capital, which is much lighter in 100 shade.

The lower molding of the cornice, g², which extends across the front, is broken by rounded necks, g³, which serve as caps for the brack-

ets, F, and above these caps are the bold niches, g^4 , which break the molding of the cornice. These are rectangular in outline and may have busts or vases set in them to give a massive appearance to the cornice. The brackets, F, have the edges above each side plain, and curved from the back of the lower part of the frieze to the front of the cornice, the sides framing transverse beveled edge strips of polished glass, mirrors, or other reflecting surface.

In the frieze, between the brackets, F, and against the sides of them, are small tapering cluster columns, h, which support arches, II, the arches curving outwardly from the column to the lower molding of the cornice. The arch curves from the capital of one set of columns to the other, forming recesses, I. The recessed panels are enriched with orna-

ments of polished material, each ornament 20 consisting of two sections of globes, apparently bound together by foliage twining around their sides and upper portions. The curve of the arch is enriched by a carved rounded molding, h', and from underneath 25 the arch drop incandescent electric globes, h², which, when lighted, reflect upon the ornament in the panel and heighten the effect of the cornice.

What I claim as new, and desire to secure 30 by Letters Patent, is—

The design for a wall fixture for counters, substantially as shown and described.

WILLIAM C. HUSS.
